UNITED STATES PATENT OFFICE.

MATTHEW R. HULL, OF CONNERSVILLE, INDIANA, ASSIGNOR TO RIX BUGGY COMPANY,
OF CONNERSVILLE, INDIANA, A CORPORATION OF INDIANA.

DOOR FOR VEHICLE-BODY TOP EXTENSIONS.

1,284,349.

Specification of Letters Patent.

Patented Nov. 12, 1918.

Application filed April 6, 1915. Serial No. 19,444.

To all whom it may concern:

Be it known that I, MATTHEW R. HULL, a citizen of the United States, residing at Connerville, in the county of Fayette and State of Indiana, have invented certain new and useful Improvements in Doors for Vehicle-Body Top Extensions, of which the following is a specification.

This invention relates to removable tops for converting automobiles with open bodies into closed-body machines to which access is had through hinged doors. The object is to provide a removable top which will be applicable to the open-body machines with hinged doors now in common use, and the invention is more particularly directed to the attachment of the door extension to the door in the open body whereby the two may swing about different hinge axes without interfering with each other or becoming separated.

The object, also, is to provide means in the door extension for manipulating the latch in the door below, of the open body, from the outside.

I accomplish the above and other objects which will hereinafter appear, by the mechanism illustrated in the accompanying drawings, in which—

Figure 1, is a view in side elevation of an open body converted into a closed one by the addition of a removable top to it, and showing my improved door construction with the doors closed; Fig. 2, a section on the line 2—2 of Fig. 1, with the door open and showing its inner side; Fig. 3, fragments of the upper and lower door members on a larger scale, showing the channel bar at their joint broken away in part; Fig. 4 a top plan view of the channel bar with the pin belonging to the upper door-member in operative position; Fig. 5 a vertical section on the lines 5—5 of Figs. 3 and 4; Fig. 6 a section on the lines 6—6 of Figs. 3 and 4 showing the upper and lower door members out of alinement, and Fig. 7 a perspective view of portions of the inner sides of the door members illustrating the latch mechanism on a larger scale than same is shown in Fig. 2.

Like characters of reference indicate like parts throughout the several views of the drawings.

The topless or open body 8 may be of any suitable and well-known construction hav-

ing doors 9, hinged in the usual manner at 10 and provided with a latch 11 operated by a knob 12. The sides of the bodies do not stand as a usual thing in vertical planes, but are contracted toward the bottom and generally on curved lines, as shown. The removable top 13 rests upon the upper edge of the open body 8, where it is retained by suitable means.

The sides of the removable top 13 are generally more nearly perpendicular than those of the body 8, whereby, a door hinged to the top member will swing on a different hinge axis from its mate below and will thereby require a constant adjustment relative to said lower door. The upper door, or rather door-member 14, is here shown as having but a single upper hinge 15, but it may have two hinges or more than two if desired. The lower edge of the door fits loosely in the channel of a channel-bar 16, secured to the upper edge of the door 9, by screws 17 and 18. A transverse slot 19, in the inner end of the channel-bar or end next to the hinged edge of the door is for the passage of the screw 18, and the length of the slot affords a limited swinging adjustment for the bar and a corresponding adjustment for the two door members.

Located in the channel near its outer end is a plate which is riveted to the channel-bar and which has an eye or loop 20, transverse to the bar and extending a suitable distance above the bottom of the bar. A notch 21 is formed in the lower edge of the top door-member 14 to receive the loop 20, and fastened to the lower edge of the door-member 14 is a plate with a pin 23 which projects into the notch and through the eye or loop 20, in the manner shown.

The extent of the opening in the loop 20 is sufficient to allow the adjacent outer corners of the doors 9 and 14 to separate as required for their proper adjustment when opened, due to their different hinging, and this adjustment is assisted by the movement of the loop longitudinally of the pin 21, and also by the swinging of the channel-bar 16 about screw 17 as a pivot. As the top door-member is not rigidly fastened to the lower one it automatically and easily adjusts itself to the latter as the two are opened and closed.

The lower door-member 9 is equipped with the usual spring-latch 11, having a bolt

24 pressed out by a spring 26, and retracted by a lever 25, terminating with a knob 12. For outside manipulation of this latch by means carried by the top door-member 14, I provide a bent lever 28, which is pivoted at its upper end to the door and terminates at its lower end with a flattened member having a longitudinal slot 27, through which the stem of the knob 12 passes. The slot 10 allows for adjustment when the lever 28 is swung and also when the door-members change their relative positions at opening and closing. The rod 28 has a lateral extension passing through a slot 29 in the 15 door concentric with the pivot at the upper end of the rod, and said extension terminates outside with a knob 30, by which the rod is manipulated to throw the latch in the door-member below.

20 Having thus fully described my invention what I claim as new and wish to secure by Letters Patent of the United States, is—

1. A vehicle door in a plurality of transversely divided members each hinged on one 25 vertical edge each occupying a different plane when the door is closed, a channel bar extending approximately the full width of the door, located at the joint, and secured to one door member and receiving the edge of 30 the adjacent member in its channel, said channel bar having a movement relative to one of the door sections.

2. A vehicle door in a plurality of transversely divided members each occupying a 35 different plane when the door is closed, a channel bar at the joint secured to one door member and receiving the edge of the adjacent member in its channel, said channel bar having a limited swinging adjustment 40 on its outer end.

3. A vehicle door in a plurality of transversely divided members each occupying a different plane when the door is closed, a channel bar at the joint secured to one door member and receiving the edge of the adjacent member in its channel, said channel bar having a limited swinging adjustment on its outer end, and means to limit the adjustment of the inserted member in the channel. 45

4. A vehicle door in two transversely divided members each in a different plane when the door is closed, a single hinge for the upper door member and a plurality of hinges for the lower door member, a channel bar secured in the joint between the 50 members to the lower door member and receiving the lower edge of the upper door member, and means for limiting the movement of the inserted door member in the 55 channel. 60

5. A vehicle door in two transversely divided members each in a different plane when the door is closed, a single hinge for the upper door member and a plurality of hinges for the lower door member, a channel bar secured in the joint between the members 65 to the lower door member and receiving the lower edge of the upper door member, said bar having a limited swinging adjustment 70 on its outer end, and a pin and loop means for limiting the movement of the inserted door member in the channel. 70

In witness whereof I have hereunto set my hand and seal at Connersville, Indiana, this 31st day of March, A. D. one thousand 75 nine hundred and fifteen.

MATTHEW R. HULL. [L.S.]
